UNITED STATES PATENT OFFICE

2,368,112

APPARATUS FOR PELLETING CARBON
BLACK

Samuel C. Carney, Bartlesville, Okla., assignor to
Phillips Petroleum Company, a corporation of
Delaware

Original application June 12, 1939, Serial No.
278,753. Divided and this application November
29, 1941, Serial No. 421,054

3 Claims. (Cl. 258—180)

This invention relates to the art of transforming the dusty light pulverulent material as produced, into free flowing, relatively dustless, small aggregates with density of 20 pounds or more per cubic foot and is an improvement over my co-pending application, Serial No. 259,065, filed February 28, 1939, and now matured into U. S. Patent 2,311,154, and is a division of applicant's co-pending application Serial No. 278,753, filed June 12, 1939, and now matured into U. S. Patent 2,294,022.

An object of this invention is to furnish an apparatus for the pelleting of such pulverulent material as carbon black.

Another object of this invention is to furnish an apparatus which is simple in design and inexpensive to construct and operate for the pelleting of such materials as carbon black.

Still other objects and advantages of my invention will be apparent from a careful study of the following disclosure. The operation of the apparatus herein described and claimed may be fully understood on reference to my issued patent, No. 2,294,022, of which this present application is a division.

In the accompanying drawings, forming a part of this specification, and in which like numerals are employed to designate like parts throughout the same,

Figure 1 shows diagrammatically a layout of the apparatus for carrying forward the process,

Figure 2 shows a vertical view of the hoppers and down flow lines;

Figure 3 is a plan view of that portion of the apparatus below the section line 3—3;

Figure 4 is a plan view of that portion of the apparatus below the section line 4—4; and

Figure 5 is a plan view of that portion of the apparatus above the section line 5—5.

Referring to Figure 1 of the drawings, the major parts or members, shown diagrammatically, are the "seed mill" apparatus shown to the left in this figure, the apparatus to the right constitutes the "pellet mill" in which the desired product is made. Numerals 13 and 29 refer to vibrating screens for sizing of materials in process, vibrator 13 being used in conjunction with the seed mill circuit while vibrator 29 serves to separate product, oversize and undersize material produced within the pellet mill circuit. Numerals 1 and 2 refer to material elevators, and these may be of substantially standard type and construction provided they are adapted to elevating relatively fine materials.

For a full and detailed description of this plant

layout, reference should be made to my patent, No. 2,294,022.

The apparatus of this invention, that is, the "pellet mill" proper is shown in more detail in Figures 2—5. While the apparatus and construction details are fully described hereinafter, the operation of this pellet mill is fully described in the above said patent.

Figures 2—5 show the details of the down flow tubes and also show an adjusting arrangement to vary the slope of the hose members. The numeral 50 represents the bottom of the upper feed hopper 20 and is shown in plan in Figure 5. It is of circular shape and stationary with the rubber tubes 21, 22, 23 and 24 connected to it by means of ball and socket joints 51, 52, 53 and 54, so that the connection is free to rotate or to change its angular direction. A circular plate 55 is located at the top of the lower hopper. It is circular and of the same diameter as the plate 50 and it is so mounted that it may be rotated by a worm or gear arrangement. The plate 55 has the gear 56 on its outer edge and the gear wheel 57 meshes with the gear 58 on the plate 55. A shaft 58 and wheel 59 connect with the gear wheel 57 to turn the plate 55.

The delivery ends of the hose are connected into openings near the edge of the plate 55 also by movable joints 60, 61, 62 and 63 except 64, 65, 66 and 67 represent telescopic joints in addition to the ball and socket joints. The telescopic joints 64, 65, 66 and 67 are of metal but rubber lined and are capable of extension in length of about 4 feet. These helical tubes are so constructed and adjusted in cooperation with the above said telescopic joints and movable joints that the material flowing downward therethrough discharges directly by gravity into the lower or receiving hopper 25.

40 A stationary mast of 2 inch pipe 68, for example, extends between the centers of plates 50 and 55. Its function is solely to align the guides 69 and 70 which are loosely mounted on the stationary mast 68, free to rotate about it or move up and down. Their only function is to guide and space the rubber tubes and to hold constant the diameter of the helix in which the tubes are arranged. Any suitable number of such members 69 and 70 are used depending on the distance between 50 and 55. To the edges of 69 and 70 are loosely attached as by a swivel joint, clamps 71 and 72. By their attachment to the plurality of tubes, these clamps hold the spacing members 69 and 70 in their relative positions.

Plate 55 is arranged to be rotated by the gear

mechanism 56, 57, 58 and 59. Though probably unnecessary, it is explained that such rotation is not constant but is only a means for adjustment by the operator of the slope of the spiral. To do this the operator may occasionally rotate disc 58, for example, one-quarter or one-half revolution, either forward or backward. If he turns it in a direction to increase the number of turns in the helix, the rubber members will have to lengthen and this is the function of the telescopic joints 64, 65, 66 and 67 with which each of the tubes is equipped. It is noted that four feet of change in the length of tubes is sufficient for all desirable adjustments in slope when the diameter of the helix is 2 feet and the distance between plates 56 and 55 is 30 feet.

It is to be understood that the form of my invention, herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. Apparatus for making granular an agglomerative powder which is fine and dry comprising a container to receive a cyclic stream of free flowing granules, a second container located below the first mentioned container, helical conduit means between the upper and lower containers having a sufficient angle of slope that the flow of granules from the upper container to the lower will be by gravity, and means for adjusting the angle of slope of the helical conduit means while

15 maintaining the diameter of the helical conduit means substantially constant.

2. Apparatus for making granular an agglomerative powder which is fine and dry comprising a container to receive a cyclic stream of free flowing granules, a second container located below the first mentioned container, extensible helical conduit means between the upper and lower containers having a sufficient angle of slope that the 10 flow of granules from the upper container to the lower will be by gravity, and means for adjusting the angle of slope of the helical conduit means and for simultaneously varying the length thereof while maintaining the diameter of the helical extensible conduit means substantially constant.

20 3. Apparatus for making granular an agglomerative powder which is fine and dry comprising a container to receive a cyclic stream of free flowing granules, a second container located a predetermined distance below the first mentioned container, extensible helical conduit means between the upper and lower containers and permanently attached to both of said containers, said conduit means having a sufficient angle of slope that the 25 flow of granules from the upper container to the lower will be by gravity, and means for varying the length of the extensible helical conduit means and for adjusting the angle of slope of the conduit means without changing said distance between the containers while maintaining the diameter of the helical extensible conduit means substantially constant.

SAMUEL C. CARNEY.
